CLAIM

The ornamental design for a condensate neutralizer device, as shown and described.

DESCRIPTION

FIG. 1 is a top right front view of a condensate neutralizer device.

FIG. 2 is a bottom left rear view thereof.

FIG. 3 is a top left view thereof.

FIG. 4 is a top view thereof.

FIG. 5 is a bottom view thereof.

FIG. 6 is a front view thereof.

FIG. 7 is a rear view thereof.

FIG. 8 is a right side view thereof; and,

FIG. 9 is a left side view thereof.

The rectangular and circular features disposed on the front portion of the right side of the condensate neutralizer device as shown in FIGS. 1 and 8, the circular features disposed on the lower portion of the front of the condensate neutralizer device as shown in FIGS. 1, 3, 6 and 8-9, the combined rectangular, trapezoidal and semi-circular features disposed on the bottom portion as shown in FIGS. 2 and 5, the two ports disposed on the rear of the condensate neutralizer device as shown in FIGS. 2-5 and 7-9 and the broken lines shown throughout the views represent the portions of the design that form no part of the claim.
